US0D1065241S

(12) United States Design Patent (10) Patent No.: US D1,065,241 S
(45) Date of Patent:  Mar. 4, 2025

(54) DISPLAY SCREEN OR PORTION THEREOF WITH A GRAPHICAL USER INTERFACE

(71) Applicant: IGT, Las Vegas, NV (US)

(72) Inventors: Sandra Eibl, Kalsdorf bei Graz (AT);
Caprice Mitterhöfer Klein, Graz (AT);
Gerhard Pichler, Graz (AT)

(73) Assignee: IGT, Las Vegas, NV (US)

() Term: 15 Years

(21) Appl. No.: 29/945,400

(22) Filed: Jun. 3, 2024
